CLAIM

I claim the ornamental design for a knob, as shown and described.

DESCRIPTION

FIG. 1 is a perspective view of the knob according to a preferred embodiment.

FIG. 2 is a top plan view of the knob.

FIG. 3 is a front elevation view of the knob.

FIG. 4 is a side elevation view of the knob.

FIG. 5 is a bottom plan view of the knob.

FIG. 6 is a perspective view of the knob according to an alternative embodiment.

FIG. 7 is a top plan view of the knob as shown in FIG. 6.

FIG. 8 is a front elevation view of the knob as shown in FIG. 6; and,

FIG. 9 is a side elevation view of the knob as shown in FIG. 6.

The broken lines at the base of the stem represent the bounds of the claim and all others are for illustrative purposes only. None of the broken lines form a part of the claimed design.

The surface(s) or portion(s) of the article not shown in the drawing or described in the specification form(s) no part of the claimed design.
